MULTIRANGE RECEIVER

Walter van B. Roberts, Princeton, N. J., assignor
to Radio Corporation of America, a corpora-
tion of Delaware

Application October 26, 1933, Serial No. 695,224

10 Claims. (Cl. 250—40)

My present invention relates to radio receivers, and more particularly to an improved tuning means for multi-range receivers.

A multi-range receiver as employed in the present invention indicates a receiver which is capable of receiving signals over a very wide range of frequencies, such as 20,000,000 cycles. In such a multi-range receiver there is usually employed a switching means for selecting particular narrow bands within the complete range of the receiver. Since the widest audio channel is only about 10,000 cycles wide, there may be some 2,000 different adjustments in a frequency range of 20 megacycles, any one of which might be correct for reception of a station. To successively tune the receiver to each of these 2,000 different adjustments in the search for a signal of unknown frequency is a tedious job, even if the receiver is designed to permit of the simplest uni-control operation. The reason for this is that if the range is covered in too short a time, the station hunted for would be passed over too quickly to notice.

Accordingly, it is one of the main objects of the present invention to tune through a plurality of tuning bands of a very wide frequency range simultaneously, and to provide a means for rendering the receiver simultaneously sensitive to all of such tuning bands, there being means for rendering the receiver insensitive to all but one of said bands.

Another object of the present invention is to provide a multi-range receiver which is adapted to cover a very wide frequency range in a simple and efficient manner, the receiver being provided with a plurality of networks including cascaded resonant circuits, each network being tunable through a predetermined band of the very wide frequency range, and each circuit of a network being provided with a switch for selectively connecting or disconnecting the associated circuit from a given amplifier.

Still another object of the invention may be stated to reside in the provision in a multi-range receiver of a plurality of cascaded amplifier tubes, and a coupling network between each pair of successive tubes, which includes a plurality of resonant circuits, each resonant circuit being adapted to be tuned through a different tuning band of the entire frequency range, there additionally being provided switches in each network for selectively eliminating one or more of its degrees of freedom.

Still other objects of the invention are to im-
prove generally the simplicity and efficiency of

multi-range receivers, and to particularly provide such a receiver which is not only economically manufactured and assembled, but reliable in operation.

The novel features which I believe to be characteristic of my invention are set forth in particularity in the appended claims. The invention itself, however, both as to its organization and method of operation will best be understood by reference to the following description, taken in connection with the drawing, in which I have indicated diagrammatically a circuit organization whereby my invention may be carried into effect.

The receiver in the accompanying drawing is shown as of the tuned radio frequency amplifier type, but it is to be clearly understood that it may be of the superheterodyne type. The signal collector A is the customary grounded antenna circuit, but it may be replaced by a radio distribution system, or it may be a loop antenna. The first tube 1, of the screen grid type, has its input electrodes connected across the variable resistor 2, the latter being arranged in series in the antenna circuit. The resistor 2 functions as a manual volume control element, but it is to be understood that any other well known type of amplifier output control device may be employed.

The anode circuit of tube 1 includes a plurality of coils arranged in series relation. For illustrative purposes three such coils 3, 4 and 5 are shown arranged in series between the anode of tube 1 and the positive side of the usual potential source B. These coils are the primary coils of radio frequency coupling transformers, whose secondaries are coils 3', 4' and 5' respectively. The secondary coils are arranged in series between the control grid of screen grid tube 6 and ground. Variable tuning condensers 7, 8 and 9 are connected across coils 3', 4' and 5' respectively. Each of these tuning condensers is constructed with respect to its associated coil to tune its resonant circuit over a predetermined frequency band of the multi-band frequency range of the receiver. The amplifier tube 6 has its cathode grounded through the usual grid bias network 10, while its anode is connected to a point on source B of appropriate positive potential.

A switch is arranged in shunt with each of condensers 7, 8 and 9, and these switches function to selectively render amplifier 6 insensitive for a desired one of the tuning bands corresponding to the resonant circuits connected in the grid circuit of the amplifier tube 6. Thus, the open-

ing of switch 11, and the closing of switches 12 and 13 renders the amplifier 6 sensitive solely for those frequencies lying within the tuning range of the band over which the resonant circuit 5 including condenser 7 is operative. By virtue of the closing of switches 12 and 13 the amplifier 6 is insensitive to the frequencies lying within the bands corresponding to the resonant circuits including condensers 8 and 9. For the purpose 10 of reference, switch 11 has been designated in the drawing as controlling the operation within a band "A", while switch 12 controls operation in band "B", and switch 13 controls operation in band "C". It is to be understood that these 15 three bands may be adjacent, spaced, or even overlapping. Furthermore, each of these bands may have a frequency coverage which is relatively wide or relatively narrow.

The screen grid tube 6', following the tube 6, 20 is shown as being arranged for functioning as a detector. The grounded cathode circuit of the tube 6' includes a grid biasing network 10', and those skilled in the art will understand that the constants of this network are so chosen that the 25 tube 6' functions as a bias detector by virtue of plate rectification. The circuit between the anode of tube 6 and the grid of tube 6' is a duplicate of the circuit between the anode of tube 1 and the grid of tube 6. Thus, there is arranged in the 30 anode circuit of tube 6 the three primary coils which correspond to the primary coils 3, 4 and 5. Each of these primary coils is coupled to a secondary coil in the same manner as in the case of secondary coils 3', 4' and 5'. Again, the tuning condensers 7', 8' and 9' connected across 35 the secondary coils in the grid circuit of tube 6' are similar to the condensers 7, 8 and 9 respectively. Additionally, the switches 11, 12 and 13 find their counterparts 11', 12' and 13' in the 40 resonant circuits arranged in the grid circuit of tube 6'.

The dotted line 20 is to be understood as illustrating a conventional mechanical coupling between the switches 11 and 11', so that these two 45 switches may be opened and closed simultaneously. Dotted line 20' illustrates the mechanical coupling between the switches 12 and 12', while the dotted line 21 represents the mechanical coupling between switches 13 and 13'. The tuning condensers 7 and 7' have their rotors arranged for uni-control adjustment, and this mechanical adjustment is represented by the dotted line 30. The variable condensers 8 and 8' are shown arranged for mechanical uni-control, and 50 the uni-control is represented by the dotted line 30'. The variable tuning condensers 9 and 9' are shown arranged for mechanical uni-control by the dotted line 31. Finally, the ganged tuning arrangements of bands A, B and C are shown 55 arranged for simultaneous control, and this mechanical coupling between the gangs of condensers is represented by the dotted line 32. The common operating knob for the plurality of tuning bands is designated by the reference numeral 33.

The anode of the detector tube 6' is connected to a point on source B of appropriate positive potential through the primary of the audio frequency coupling transformer 40. It is to be understood that the transformer 40 connects the 70 anode circuit of detector tube 6' to one, or more, succeeding stages of audio frequency amplification, and/or a reproducer of the electrodynamic or electromagnetic type. As stated heretofore, 75 the present arrangement is not confined in its

usage to a receiver of the tuned radio frequency amplifier type, but may be embodied in a superheterodyne receiver. In such a case, the tube 6' could well be the first detector tube of the superheterodyne receiver.

5

The operation of the arrangement embodying the present invention should now be readily understood from the foregoing detailed description and the accompanying drawing. The present invention contemplates the tuning of a radio 10 receiver through a plurality of tuning bands of a predetermined frequency range simultaneously. For example, suppose there are ten such tuning bands, each 200 channels wide. Then, if the knob 33 is actuated, the search for a given signal frequency goes on simultaneously in each of these tuning bands, and the time required for searching the entire frequency range is reduced to one-tenth. Once a station is heard, the receiver may be rendered insensitive to all of the tuning bands 20 other than the one in which the station lies. In the specific case shown in the drawing, when all the switches of each tuning band are open, the receiver will respond to any signal lying within any of the three tuning bands A, B and C. 25 By closing switches 12 and 12', for example, the receiver becomes insensitive to the tuning band B. In operation, once a station is heard, and assuming that the station lies in band A, switches 12 and 12' and 13 and 13' will be closed. The closing of these latter switches minimizes interference, and renders the receiver sensitive only to the tuning band A. The particular mechanical coupling of the three condenser gangs is immaterial to the present invention. A belt, or any well 30 known type of link coupling, may be utilized between the knob 33 and the mechanical couplings 30, 30' and 31.

30

The essential feature of the invention is to provide a receiver which is simultaneously sensitive 40 to a plurality of frequencies specifically lying in different tuning bands, the receiver additionally including means for tuning it through these different tuning bands, and the receiver finally including means for rendering it insensitive to all 45 but one of a desired frequency of a given tuning band.

40

While I have indicated and described a system for carrying my invention into effect, it will be apparent to one skilled in the art that my invention is by no means limited to the particular organization shown and described, but that many modifications may be made without departing 50 from the scope of my invention, as set forth in the appended claims.

50

What I claim is:

55

1. In a radio receiver including at least two cascaded tubes, a coupling network between said tubes comprising a plurality of resonant circuits connected in series between the input electrodes 60 of the second tube, means in each of said circuits for tuning its associated circuit through a predetermined tuning range, said tuning ranges being different, a single means for simultaneously adjusting said tuning means throughout said 65 ranges, and additional means for rendering inefficient the transmission between any one of said circuits and said second tube.

60

2. In a radio receiver including at least two cascaded tubes, a coupling network between said 70 tubes comprising a plurality of resonant circuits connected in series between the input electrodes of the second tube, means in each of said circuits for tuning its associated circuit through a predetermined tuning range, said tuning ranges being dif- 75

75

ferent, a single means for simultaneously adjusting said tuning means throughout said ranges, and additional means including a switch in each of said circuits for rendering inefficient the transmission between any one of said circuits and said second tube.

3. In a radio receiver including at least two cascaded tubes, a coupling network between said tubes comprising a plurality of resonant circuits connected in series between the input electrodes of the second tube, means in each of said circuits for tuning its associated circuit through a predetermined tuning range, said tuning ranges being different, a single means for simultaneously adjusting said tuning means throughout said ranges, additional means including a switch in each of said circuits for rendering inefficient the transmission between any one of said circuits and said second tube, a third tube following said second tube, and a coupling network between said second and third tubes which is similar in construction to said first named coupling network.

4. In a radio receiver including at least two cascaded tubes, a coupling network between said tubes comprising a plurality of resonant circuits connected in series between the input electrodes of the second tube, means in each of said circuits for tuning its associated circuit through a predetermined tuning range, said tuning ranges being different, a single means for simultaneously adjusting said tuning means, additional means for rendering inefficient the transmission between any one of said circuits and said second tube, a third tube following said second tube, a coupling network between said second and third tubes including resonant circuits similar in construction to said resonant circuits of the first coupling network, and means mechanically coupling the tuning means of corresponding resonant circuits of said first and second coupling networks whereby said tuning means are adjustable by said adjusting means over said ranges.

5. A radio receiver including an amplifier provided with a plurality of tunable circuits in its input circuit, a single means for simultaneously varying the tuning of each of said circuits over a frequency range different from that of every other tunable circuit, said amplifier being simul-

taneously sensitive to the frequencies in each of said tunable circuits, and means for rendering said amplifier insensitive to all but one of said tunable circuits.

6. A multi-range receiver comprising a vacuum tube device, a plurality of tunable circuits serially connected to the input of said device, each tunable circuit being resonant to a different predetermined brand of a plurality of frequency bands which comprise the range of the receiver, separate means for tuning each of said tunable circuits, and separate means for short-circuiting each of said circuits.

7. The invention defined in claim 6 wherein the vacuum tube device comprises a radio frequency amplifier.

8. The invention defined in claim 6 wherein the vacuum tube device comprises a detector.

9. A multi-range receiver comprising a radio frequency amplifier, a detector, a plurality of series-connected tunable circuits connected to the input of the amplifier, a similar set of tunable circuits connected to the input of the detector, corresponding tunable circuits of the amplifier and detector being resonant to a different predetermined band of a plurality of frequency bands which comprise the range of the receiver, separate means for tuning each of said tunable circuits, and separate means for short-circuiting each of said circuits.

10. A multi-range receiver comprising a radio frequency amplifier, a detector, a plurality of series-connected tunable circuits connected to the input of the amplifier, a similar set of tunable circuits connected to the input of the detector, corresponding tunable circuits of the amplifier and detector being resonant to a different predetermined band of frequencies within the range of the receiver, separate means for tuning each of said tunable circuits, means for controlling in unison the operation of all said separate tuning means, separate means for short-circuiting each of the tunable circuits, and means for controlling in unison the operation of the separate short-circuiting means associated with the tunable circuits of the amplifier and detector which are resonant to the same frequency band.

WALTER VAN B. ROBERTS.
